CLAIM

The ornamental design for a pet collar as shown and described.

DESCRIPTION

FIG. 1 is a perspective view of a pet collar showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is an enlarged view of portion 9 shown in FIG. 1. The long-dash dot-dot broken lines in FIGS. 1 and 9 represent boundaries for the enlarged views shown in FIG. 9, and form no part of the claimed design.

The short dash-dot broken lines in the drawings depict portions of the pet collar that form no part of the claimed design.

The long-dash short-dash broken lines depict the contours of the pet collar that form no part of the claimed design.
